(57) **CLAIM**

The ornamental design for a decorative enclosure for a fire extinguisher, as shown and described.

DESCRIPTION

FIG. 1, illustrates an exploded front view of a decorative enclosure for a fire extinguisher showing our new and ornamental design, shown in the opened condition thereof; FIG. 2 illustrates a front view in the closed condition thereof;

FIG. 3 illustrates a rear view thereof;

FIG. 4 illustrates a left side view thereof;

FIG. 5 illustrates a right side view thereof;

FIG. 6 illustrates a top plan view thereof; and,

FIG. 7 illustrates a bottom plan view thereof.

The broken lines showing a fire extinguisher in FIG. 1 are for illustrative purposes only and do not form part of the claimed design.

1 Claim, 2 Drawing Sheets

FIG. 1

FIG. 2
